UNITED STATES PATENT OFFICE.

JOHN L. DINSMOOR, OF BROOKLYN, NEW YORK, ASSIGNOR TO ANCHOR CAP AND CLOSURE CORPORATION, OF LONG ISLAND CITY, NEW YORK, A CORPORATION OF NEW YORK.

SEAL.

Application filed June 10, 1921. Serial No. 476,390.

To all whom it may concern:

Be it known that I, JOHN L. DINSMOOR, a citizen of the United States, and a resident of the borough of Brooklyn, in the county of Kings, State of New York, have invented new and useful Improvements in Seals, of which the following is a specification.

This invention relates to seals of the shackle variety and resides particularly in 10 the provision of novel means for securing a shackle to a keeper in such fashion as to provide a permanent connection which does not admit of detachment or tampering without detection.

15 The general purpose of the invention is to provide a form of seal which may be constructed at a very low cost and used without special appliances and at the same time afford the necessary security and safeguard 20 against alteration or tampering.

A more specific object of the invention is the provision of a form of seal which may be made and assembled entirely by punching operations, thereby facilitating the manufacture 25 of the articles in large quantities and at small labor cost.

A more specific object of the invention is the provision of a form of shackle seal wherein 30 a keeper is provided for securing and housing the ends of a shackle, the keeper being operable originally to deform or twist together the ends of the shackle in such fashion as to prevent detachment of the shackle from the keeper and to effectively enclose 35 and protect the secured portions so as to prevent their being straightened or untwisted to permit their withdrawal from the keeper.

Other and further objects will be obvious 40 upon an understanding of the invention, or will be hereafter pointed out or suggested, or will be indicated in the appended claims. The drawings show an illustrative embodiment 45 of the invention, the same being merely one of a great variety of forms in which it may be incorporated.

In said drawings Figure 1 is a longitudinal section through the keeper showing the shackle in its secured or twisted condition;

50 Figure 2 is a longitudinal section through the keeper at right-angles to Figure 1;

Figure 3 is a top or end view of the keeper;

Figure 4 is a perspective illustrating a

step in the construction of the barrel portion of the keeper illustrated in Figures 1 and 2;

Figure 5 is a longitudinal sectional view illustrating a modified form of the barrel portion;

Figure 6 is a view illustrating a modified form of shackle and its manner of application to a keeper, while

Figures 7 and 8 are perspective views illustrating modified forms of shackles.

Referring to these illustrations by means of the reference numerals applied, let it be understood that the numeral 1 designates generally the shackle portion of the seal. This may be in the form of a ductile strip such as a wire or a ribbon of metal, and it 70 may be provided with the customary identifying characters 1^a and detecting characters 1^b adjacent the point at which it is designed to enter the keeper. The keeper is formed of relatively movable parts comprising a barrel 2 and a closure 4. These are arranged so that they are susceptible of relative rotation while at the same time they are permanently connected to form a receptacle. The barrel may be constructed in the form 75 illustrated by drawing a blank into the frusto-conical shape illustrated in Figure 4 and then compressing the walls adjacent the smaller diameter so as to flatten them to the form illustrated in Figure 2.

The closure may be in the form of a metal plate with the apertures 4^a arranged about its middle, and the closure and barrel may be secured together by having the marginal portion of the former flanged over a peripheral flange 2^a of the latter, as illustrated at 85 4^b, the connection being such as to permit relative rotation of the two members on an axis longitudinal of the barrel. The metal of the closure adjacent the apertures 4^a, including an intervening strip 4^c, constitutes what I will term a connecting portion, as it constitutes means of connection or attachment to the shackle. The portion of the barrel indicated at 2^c, which I will term 100 the retaining portion, is disposed substantially in alignment with the apertures 4^a, longitudinally of the keeper, and is of proper width to receive, with a fairly close fit, the end portions of the shackle, and to 105 act effectively in retaining them against

relative rotation and against rotation relative to the barrel member. In the compressing of the walls of the conical blank the portion constituting the small base or 5 end of the cone frustum folds inwardly to provide a spacing member 2^a which gives the proper spacing to the walls of the retaining portion 2^c.

In the utilization of the device, the 10 shackle is passed through the intended loop to which the seal is to be attached, and the end portions are inserted through the apertures 4^a and into the retaining portion 2^c. The closure member and barrel then being 15 given relative rotation, which is done simply by manipulation with the fingers, the end portions of the shackle will be twisted together within the keeper, in the manner illustrated at 1^a in Figure 1. This twisting 20 together of the end portions of the shackle joins or distorts them in such fashion as to prevent their withdrawal through the apertures 4^a, the connecting portion of the keeper operating effectively to retain them, 25 and incident to this twisting of the end portions of the shackle, their extent within the keeper is shortened, due to their being doubled over one upon another, so that they are finally withdrawn automatically from the 30 engagement of the engaging portion 2^c. Relative rotation of the barrel and closure members being continued until they are movable entirely freely, operates effectively to bend the ends of the shackle to a position 35 or form in which they cannot be re-engaged in the retaining portion 2^c. Thus reverse rotation of the barrel and closure will not operate to untwist or straighten out the deformed portions of the shackle.

40 This firmly secures the shackle and keeper together, the portions of the former whereby the connection is perfected being completely enclosed and within the keeper and protected against tampering. The application of force by relative traction upon the 45 shackle and keeper in an attempt to cause the former to straighten out, will simply rupture the metal of the closure, rendering it plainly evident that the seal has been violated.

In order to insure complete engagement 50 of the ends of the shackle in the retaining portion, they may be formed in the manner illustrated in Figure 6, wherein the extremities are doubled back to provide gauge members 1^c. These provide spacers in requiring 55 that the extremities of the shackle be completely inserted in the engaging portion 2^c in order that the portions 1^c may be entirely 60 inserted through the apertures 4^a. In Figure 5 is illustrated a variation of the form of barrel, the retaining portion being formed by an obstruction such as designated by the numeral 5 placed in the lower portion 65 of the barrel in such fashion as to re-

tain the ends of the shackle against relative rotation, or against rotation relative to the barrel.

Figures 7 and 8 illustrate variations in the form of shackle. Figure 7 illustrates a 70 form in which the shackle may be constructed of wire, the same being flattened at intervals to provide detecting members 6 and having it send portions flattened as at 75 7 to facilitate their distortion or twisting within the keeper. In Figure 8 the outer portion of the shackle is shown wider than the length of the apertures 4^a, the end portions of the shackle being folded back and the folded portion reduced in width so as 80 to permit their insertion through the apertures. The projecting ears 8 form detecting members, and also form means by which the seal may be tested, as any fracture of the shackle within the keeper will result in these ear portions being detached so that they would fall off, or be easily pulled off upon inspection. It is obvious, of course, that various adaptations of the embodiments 85 illustrated may be made without departing from the scope of the invention as set out in the claims. The form of the device permits the barrel being cast or molded, as of 90 glass, which will permit the inspection of 95 the contained portions of the shackle.

In the construction of the device of sheet metal, it may be made in its entirety by punching operations, one to form the barrel, and another to form the cup-shaped closure, and the third to flange the two together. It 100 is obvious that this will contribute to the construction of the device at a very low cost.

Having thus described my invention, what I claim is:

1. A seal comprising a ductile shackle and a keeper, the latter including relatively rotatable members arranged to enclose end parts of the shackle and having portions arranged to engage parts of the shackle to 110 cause it to be twisted upon relative rotation of said members, one of said portions affording means of permanent attachment to the shackle and another of said portions affording a temporary attachment to the 115 shackle, which is automatically disengaged upon twisting thereof.

2. A seal comprising a ductile shackle and a keeper, the latter including relatively rotatable members arranged to receive and 120 enclose end parts of the shackle, said members having portions effective to engage parts of the shackle at points spaced apart thereon to effect distortion of said parts upon rotation of said members, one of said 125 portions being automatically disengaged from the shackle upon predetermined distortion thereof.

3. A seal comprising a ductile shackle and a keeper arranged for the introduction of 130

- end portions of the shackle thereinto; said keeper including relatively rotatable portions one of which is adapted for permanent engagement with the shackle and the other for temporary engagement therewith to effect distortion of the shackle within the keeper upon relative rotation of said parts.
4. A seal comprising a ductile shackle and a keeper including a barrel member and a closure connected to provide a receptacle for the ends of the shackle, said barrel and closure portions being relatively rotatable and having portions spaced apart longitudinally of their axis for separately engaging the shackle to effect its distortion upon their relative movement.
5. A seal comprising the combination of a ductile shackle and a keeper constructed to afford a receptacle for end portions thereof, said keeper including a relatively rotatable barrel and a closure, the latter being apertured to permit the introduction of the shackle into the barrel, and said barrel including an engaging portion directed toward the apertured portion of the closure for the reception of the extremities of the shackle, said engaging portion being spaced apart from the closure longitudinally of the axis of the barrel.
6. A seal comprising a ductile shackle and a keeper, the latter being formed as a receptacle apertured to permit the insertion of end portions of the shackle and including an engaging member movable relative to the shackle and adapted for temporary engagement therewith to effect distortion thereof within the keeper.
7. A seal comprising a ductile shackle and a keeper, the latter being formed as a receptacle apertured to permit the insertion of end portions of the shackle and including an engaging member movable relative to the shackle and adapted for temporary engagement therewith to effect distortion thereof within the keeper and including an engaging member movable relative to the shackle and adapted for temporary engagement therewith to effect distortion thereof within the keeper, said engaging member being arranged to permit disengagement of the shackle therefrom within the keeper automatically upon predetermined distortion of the shackle.
8. A seal comprising a ductile shackle and a keeper, the latter including a closure portion apertured to permit insertion of end portions of the shackle and effective to retain the shackle against relative rotation, and a barrel member attached to the closure and rotatable thereon, said barrel member including an engaging portion arranged to engage a portion of the shackle and cause it to be twisted about its longitudinal dimension upon relative rotation of the closure and barrel.
9. A seal comprising a shackle having ductile end portions, and a keeper, the latter including relatively movable members arranged to enclose end portions of the shackle, one of said members including a connection portion adapted to engage the shackle, and the other of said members including an engaging portion arranged to engage portions of the shackle within the keeper to effect distortion thereof, said engaging portion being automatically disengageable from portions of the shackle within the keeper upon predetermined relative movement of said members.

JOHN L. DINSMOOR.
